ROLL HANDLING TOOL

Wentzel R. Duda, Pittsburgh, Pa., assignor to
 Continental Roll and Steel Foundry Company,
 a corporation of Delaware

Application July 26, 1938, Serial No. 221,335

2 Claims. (Cl. 294—67)

My invention relates to tools for use in handling rolls and the like, and is hereinafter described as more particularly employed in placing and removing mill rolls.

With those types of devices employed in moving the rolls in an endwise direction into and out of their housings, provision has heretofore been made in each lifting tool for handling rolls of only one size, which necessitates the provision of a separate lifting tool for each size of roll. Such an arrangement is objectionable not only because of the requirement for an extra lifting tool, but when changing rolls in roll stands having rolls of different sizes, as in the case of three-15 high and four-high mills, for example, the presence of two lifting tools instead of a single tool makes for confusion and interference with the handling of the rolls.

My invention has for one of its objects the provision of a single lifting tool having two or more devices thereon for engagement with rolls of different sizes, and wherein neither device will interfere with the use of the other device.

Another object of my invention is to provide a lifting tool having a roll-engaging socket which is adjustable to permit the center of gravity of the roll to be positioned in vertical alignment with the point at which the lifting force is applied to the tool.

As shown in the accompanying drawing, Figure 1 is a view showing the manner in which the lifting tool is employed in placing and removing rolls from their housings; Fig. 2 is a sectional view on an enlarged scale of a portion of the lifting tool of Fig. 1; and Fig. 3 is an inner end view of the structure of Fig. 2.

The lifting tool is shown as employed in connection with the placement and removal of rolls with respect to their housings 4. The view illustrates a three-high mill wherein a small roll 5 is disposed between larger rolls 6 and 7.

The lifting tool is in the form of a casting or the like, having a horizontal leg portion 8 and a vertical leg portion 9. A pin 10 extends through the upper leg portion for engagement by a hook 11 of a crane, not shown. A counter-balance 12 is slid upon the leg 8 and held in position thereon by a pin or bolt 13 that extends through the members 8 and 12. The member 8 serves as a counter-balance to maintain the lifting tool with its leg 9 in approximately a vertical position, when the lifting tool is free of a roll. At its lower end the leg 9 is provided with a socket-like extension 14, of a diameter and contour to fit the wobbler portion 15 of the larger roll.

In using the apparatus, the crane is shifted to move the socket 14 over the wobbler 15, in a direction lengthwise of the roll. The lifting tool is so designed that ordinarily the center of gravity of the roll 6 will be in direct vertical alignment with the lifting hook 11, so that the roll will be supported in approximately a horizontal position, and can therefore readily be moved into and from the roll housings. While the internal diameter of the socket 14 is such that it can readily be moved into position surrounding a wobbler, there is such small clearance between the socket and the wobbler that the roll will not tilt to any great degree when it is being suspended by the lifting tool.

In order to handle rolls of a smaller size which have correspondingly smaller wobbler portions, a second socket 16 is positioned within the socket 14 for slidable but non-rotatable movement therein. A screw stud or shaft 17 is rigidly secured to the socket 16 and extends rearwardly thereof, the shaft having a threaded portion that extends through the rear wall of the socket 14. The shaft 17 has screw threaded engagement with a bushing 18 that is rotatably supported within the rear wall of the socket 14 and has keyed thereto at its rear end a hand wheel 19. It will be seen that when the hand wheel 19 and consequently the bushing 18 are rotated, the socket 16 will be moved axially of the socket 14. A lubricant conduit 20 is provided to permit lubrication of the screw.

With the socket 16 in its rearmost position, as shown in Fig. 2, it is sufficiently far from the mouth of the socket 14 as not to interfere with the use of the socket 14 in handling the large rolls. When the smaller rolls are to be handled, the hand wheel 19 is turned to advance the socket 16 to the inner end of the socket 14, whereupon the socket 16 can be moved into engagement with the wobbler of the smaller roll, and such smaller roll then handled in the same manner as the larger rolls are handled.

Another advantage in providing an adjustable socket such as the socket 16, resides in the fact that it can be adjusted for use with rolls of different lengths, the adjustment being so made that the center of gravity of a roll suspended therefrom will be in vertical alignment with the lifting hook 11.

I claim as my invention:

1. A tool for handling rolls, comprising a normally-upright lifting member which is provided at its lower end with a laterally-extending socket formed to fit over a roll extension and being of

- greater length than is required for handling a roll, and a socket member for engaging a roll extension of smaller diameter and fitting within the first-named socket, the second-named socket member being adjustable axially, so that when its outer end is approximately flush with the outer end of the larger socket, it can be employed in the handling of small rolls, and when retracted toward the inner end of the first-named socket, it will not interfere with the handling of rolls by the larger socket.
5. A tool for handling rolls, comprising a horizontal leg, a vertical leg, a horizontally-extending socket member carried by the vertical leg and positioned to receive the end of the roll and
10. A tool for handling rolls, comprising a horizontal leg, a vertical leg, a horizontally-extending socket member carried by the vertical leg and positioned to receive the end of the roll and
15. A tool for handling rolls, comprising a horizontal leg, a vertical leg, a horizontally-extending socket member carried by the vertical leg and positioned to receive the end of the roll and

support the roll in approximately a horizontal position beneath the first-named leg, when lifting force is exerted upon the horizontal leg, and a second socket member carried by said vertical leg, for engaging a roll of smaller diameter, the second-named socket member fitting within the first-named socket and being adjustable axially, so that when its outer end is approximately flush with the outer end of the larger socket, it can be employed in the handling of small rolls, and when retracted toward the inner end of the first-named socket, it will not interfere with the handling of rolls by the larger socket.
